FIG. 1.

FIG. 2.

FIG. 3.

FIG. 4.

INVENTOR.

Reginald F. Sedgley
BY
Herbert S. Fairbanks

ATTORNEY.

UNITED STATES PATENT OFFICE

REGINALD F. SEDGLEY, OF PHILADELPHIA, PENNSYLVANIA

FIREARM

Application filed June 20, 1930. Serial No. 462,538.

In firearms which are adapted to be used in the firing of flares or signals, it is a great advantage if they can be constructed in such a manner that they can be unloaded and fired with one hand. This is especially advantageous in aviation in order that the aviator will not lose control of his plane.

One object of my invention is to devise a firearm wherein the flare or signal, or the barrel adapted to receive the shell or cartridge, or the cartridge which in itself forms the barrel, can be readily ejected by the operator without releasing his grasp of the firearm.

15 A further object of the invention is to provide novel releasing means for the barrel, shell or flare, to effect its ejection, and novel means for locking the parts in assembled condition, and releasing them when desired.

20 With the above and other objects in view, as will hereinafter more clearly appear, my invention comprehends a novel firearm which is adapted to be controlled by one hand of the user in loading, firing and ejecting the shell, flare or signal.

25 It further comprehends novel ejecting mechanism.

It further comprehends novel means for manually controlling and releasing the shell, flare or signal with the breech of the firearm, in order to permit the ejecting means to become operative in ejecting the shell, barrel, flare or signal.

30 Other novel features of construction and advantage will hereinafter more clearly appear in the detailed description and the appended claims.

For the purpose of illustrating the invention I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and the invention is not limited to the precise arrangement and organization of these instrumentalities as herein set forth.

35 Figure 1 is a side elevation of a firearm embodying my invention.

Figure 2 is an elevation, partly in section, showing the barrel in alignment with the opening in the breech and the breech being shown in section.

Figure 3 is a section on line 3—3 of Figure 2.

Figure 4 is an end view of a cartridge. Similar numerals of reference indicate corresponding parts.

Referring to the drawing:—

1 designates the stock of a firearm embodying my invention. The stock is provided in any conventional manner with a grasping portion 2, and in the stock is mounted the trigger 3. The firing action may be of any desired construction but is preferably constructed in accordance with my co-pending application Serial No. 322,204 or in conformity with my co-pending application Serial No. 354,833. I have therefore deemed it unnecessary in this application to illustrate and describe the firing action as it will be understood by those skilled in the art that the firing action effects the forward impact of the firing pin 4 against the percussion cap of the cartridge, flare or signal.

5 designates the charge holder, which, as illustrated, is in the form of a hollow barrel having a closed cap at its rearward end which is provided with a percussion cap 6. The charge holder 5 near its rear end is provided with an annular groove 7 adapted to receive a locking member 8 which is carried by a lever 9, fulcrumed in the side of the stock 1 and having a thumb contacting portion 11 to effect the outward movement of the locking member 8 and thereby the release of the charge holder 5. The locking member 8 is movable in an aperture 12 which opens into the chamber 13 of the breech 14 of the stock 1.

The ejecting mechanism comprises a pin 15 which forms an ejecting member which extends into an aperture 16 in the breech and bears against a spring 17, which, in turn, bears against the rear end of the aperture 16. The rear end of the charge holder 5 preferably has its outer edge chamfered as at 18. In a similar manner the locking member 8 is chamfered as at 19 in order to pro-

vide bevelled or inclined surfaces to facilitate the insertion of the charge holder 5 into its locking position.

The operation of my novel firearm will now be apparent to those skilled in this art and is as follows.

It will be understood that by the term "charge holder" I intend to include any conventional type of signal, flare, cartridge, or barrel, adapted to be filled to form the equivalent of a cartridge. The charge holder 5 is insertable into the chamber 13 of the breech 14 by relative longitudinal movement of such parts and as the holder 5 is inserted into the chamber 13 it will be apparent that the locking member 8, which is provided with a spring 20 on one side of its pivot, tending to move the locking member 8 into the chamber 13, of the breech 14, will cause such locking member 8 to be moved outwardly until the annular groove 7 is in alignment with it whereupon the locking member 8 will move into the groove 7 and the parts will be retained in assembled and locked condition. As the charge holder 5 is moved into the chamber 13, it will be apparent that it will contact with the pin 15, moving the latter rearwardly, and thereby compressing the spring 17 to store up energy therein to effect the forward movement of the ejecting pin 15 and thereby the ejection of the charge holder 5 from the breech when the locking member 8 is manually released.

The charge holders 5 are carried in a case 35 or supported in any desirable manner accessible to the user, so that, assuming that he grasps the grasping portion 2 in his right hand, he can, by moving the firearm towards the charge holder, cause the holder to be automatically locked in assembled condition. He can then fire the flare or signal with the same hand which is holding the firearm, and, as soon as the flare or signal is fired he can release and eject the charge holder 5 which has been fired, by pressure of his thumb against the pressure portion 11 of the releasing and locking lever 10.

It will thus be apparent that with one hand the operator can load the firearm, fire it, and eject the charge holder, signal, or flare which has been fired.

In accordance with my present invention relative and longitudinal movement of an aligned charge holder and firearm will cause the charge holder to be automatically interlocked with the firearm and it is not necessary to manually lock the parts in position or to effect relative rotation of the parts in order to effect the locking action.

It will now be apparent that I have devised a new and useful firearm which embodies the features of advantage enumerated as desirable in the statement of the invention and the above description, and while I have, in the present instance, shown and described

a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. In a firearm, a stock provided with a breech and adapted to receive a charge holder, a spring pressed ejecting member in the path of a holder being inserted in said breech whereby said spring is brought to tension by the insertion of the charge holder, and a manually actuated lever extending longitudinally of the breech and having a locking member insertable into said breech, said holder having an annular groove to receive said locking member.

2. In a firearm, a breech having a charge holder receiving chamber at its forward end, a quick detachable charge holder having its rear end insertable into the forward end of the chamber of said breech, a manually releasable locking member for interlocking said charge holder with said breech, and a spring pressed ejecting member in the path of said charge holder when inserted into said chamber whereby said spring is brought to tension by such insertion.

3. In a firearm, a breech, a charge holder having its rear end insertable into the forward end of said breech, a spring pressed ejecting member extending towards the front end of said breech in the path of said charge holder to eject said holder from said breech, and a manually actuated movable member effective to interlock said charge holder with said breech to prevent the ejection of the charge holder from the breech and maintaining the tension on said spring pressed ejecting member when the charge holder is assembled with the breech.

4. In a firearm, a breech, a charge holder having its rear end insertable by longitudinal movement into the forward end of the breech, a spring pressed ejecting member brought to tension by such insertion, and manually actuated means to retain the charge holder assembled with the breech and retain the tension on the ejecting member and at the will of the operator release the charge holder and thereby permit the ejecting means to eject the charge holder from the forward end of the breech.

REGINALD F. SEDGLEY.
